REFRIGERATING APPARATUS

Filed Dec. 4, 1923

Fig. 58. 65-25 Inventor
By Attorneys Frederick G. Steyes,
Cooper, Herr and Denham,

UNITED STATES PATENT OFFICE.

FREDERICK G. KEYES, OF CAMBRIDGE, MASSACHUSETTS, ASSIGNOR, BY MESNE ASSIGNMENTS, TO NATIONAL REFRIGERATING COMPANY, OF BOSTON, MASSACHUSETTS, A CORPORATION OF MASSACHUSETTS.

REFRIGERATING APPARATUS.

Application filed December 4, 1923. Serial No. 678,538.

My present invention relates to refrigeration apparatus and the operation thereof, and particularly to such apparatus in which refrigeration is obtained through quickly cooling over a wide range of temperature the atmosphere in a chamber connected to a refrigerating chamber containing a liquid having a high vapor pressure. It further relates in part to such an apparatus having a still for the vaporizing of the refrigerant at certain stages of the operation of the apparatus and this application differs from companion application Serial No. 673,105, now Patent No. 1,622,522 only in the means for heating said still and in apparatus auxiliary thereto. This application then will relate particularly to such heating apparatus, its auxiliary apparatus, and the operation of the system with particular respect to said heating apparatus. Reference will be made to said application Serial No. 673,105, for particulars not readily apparent.

I have illustrated the apparatus of my invention in the accompanying drawing, in which

Fig. 1 is a diagram of my apparatus.

Fig. 2 is a broken vertical section of one of the units of the still.

Fig. 3 is a diagram of a vertical section of the refrigeration chamber showing the arrangement of electrical control apparatus therein.

The object of this invention is to provide the still of a refrigeration apparatus with both heating and cooling means which are used alternately.

A further purpose is to provide a gas heater for such a still and means for turning said heater on and off intermittently and automatically.

Referring to the drawing, part 132 is a stove casing which encloses still elements 130 and directs thereto heat from gas stove 124. Pipes 127 through holes 128 discharge and carry from element 130 refrigerant fluid passing from or to manifold 129 which connects with manifold 18. Said manifold 18 delivers fluid passing from the still through check valve 19 to condenser 16, thence through valve 73 to pipe 24 to refrigerator 25. Manifold 18 also receives fluid from refrigerator 25 through pipe 27 and check

valve 28, and permits the fluid to pass back to the still according to the pressures in the various parts of the system, as hereinafter described, and similar to the action described in said application Serial No. 673,105. The two-way valve 29 directs cooling water from supply pipe 30 either to condenser cooling coil 33 or to still cooling coil 133, and is actuated by solenoids 40 and 41 alternately, and valve 119 is actuated by solenoids 120 and 121 alternately to turn gas to and off gas stove 124, both in accordance with refrigerant liquid level in chamber 25. Solenoids 40 and 120 are energized and deenergized simultaneously. Likewise solenoids 41 and 121 are energized and deenergized simultaneously. When solenoids 40 and 120 are energized valve 29 is open to carry water to the cooling coils 133 of the still and gas valve 119 is closed. A pilot light in the stove 124, fed through pipe 125, serves to light gas stove 124 when the gas is turned on. When solenoids 41 and 121 are energized—40 and 120 being deenergized—valve 29 is open to direct water to cooling coils 33 and valve 119 is open to supply gas to stove 124.

Switches 116, 117 (a and b) and 118 are mounted on a pivoted bar (not shown) which is actuated by solenoids 52 and 53, respectively, through armatures 54 and 55. On the energization of solenoid 52 switch 116 is closed and time switch 117^a remains closed for five seconds and 118 is opened, and on the energization of solenoid 53 switch 116 is opened, and switch 118 is closed, and switch 117^b remains closed for five seconds.

Starting from the position shown in the drawing a complete cycle of operation of the apparatus of my invention is as follows. Assuming the refrigerant fluid to be in still 132 and none to be in the condenser or the refrigerator at the beginning of the cycle, float 62 is at its lowest position in chamber 25 and contact is made across contacts 64 and 65. Current then flows through solenoids 41 and 121, cooling water is sent through to condenser 16 and gas stove 124 is lighted. Upon the distillation of refrigerant to the condenser chamber and the accumulation there of a sufficient quantity to displace float 70, the condensed refrigerant is admitted to chamber 25 where after the ac-

cumulation of a sufficient quantity float 62 is raised and contact between 64 and 65 is broken.

- 6 After the accumulation of sufficient liquid in chamber 25, contact is made between 57 and 59 through the raising of 58. Solenoid 52 is thereby energized and switch 118 is opened and time switch 117^a remains open for five seconds, and switch 116 is closed.
- 10 Solenoids 40 and 120 now being energized, valves 29 and 119 are actuated respectively to send cooling fluid through condenser cooling coils 133 and to shut off the gas from stove 124. Upon the cooling of the
- 15 atmosphere in still units 130 the vapor pressure therein is lowered relieving the pressure in chamber 25, whereupon the refrigerant fluid therein evaporates and expands. In so doing it absorbs heat from the vicinity of
- 20 the refrigerator. The excess of pressure in chamber 25 over that in the still forces the vaporized refrigerant through pipe 27, through check valve 28, into unit 130 of the still. Through the cooling of these units
- 25 by the water passing through coils 133 the pressure therein is kept low enough to allow substantially all of the refrigerant to pass thereto whereupon contactor 58 again establishes a circuit through solenoid 53
- 30 whereby water is turned from coils 133 and to coils 33 and the gas is turned to stove 124, thus completing the cycle. The action goes on in cycles as described while feed mains 11 and 12 are energized.
- 35 In each of the chambers 126 is placed refrigerant absorbent and storing material which is added through the upper end of said chamber, which chamber is afterward closed with the cap 137 which may be welded
- 40 thereon and to pipes 127 and 31. On each of the distributing pipes 127 and over the holes 128 therein is placed a covering of asbestos tubing 138 to prevent dust being carried with the refrigerant as it passes in or out through said pipes.

45 The absorbent materials in the casings 126 which I contemplate using herein, among others, are ammoniated chemical compounds such as described in my application, Ser. No. 673,103, filed Nov. 6, 1923, and particularly the calcium chloride, magnesium oxychloride, alundum cement material described in said application.

I claim:

- 55 1. In a refrigerating apparatus, a still comprising an outer casing, inner casings, a cooling coil in each of said inner casings, a manifold, a delivery pipe from said manifold to each of said inner casings, and a heat source in said outer casing.
- 60 2. In a refrigerating apparatus, a still comprising an outer casing, inner casings, a cooling pipe passing through each of said inner casings, a manifold, a pipe connection between said manifold and each of said inner

casings, and a gas heater in said outer casing.

3. In refrigerating apparatus, in combination, a refrigeration chamber, expansion coils connected thereto, a condenser and condensing chamber, a still, pipe connection from said still to said condenser with a check valve therein permitting flow from said still to said condenser, pipe connection from said condenser to said refrigerator chamber, pipe connection from said refrigerator chamber to said still with a check valve therein permitting flow from the refrigerator to the still, a refrigerant in said system, a gas heater for said still, water cooling coils for said still, water cooling coils for said condenser, and means controlled by the liquid level in said refrigerator chamber for causing the gas heater to be lighted and water to pass through said condenser cooling coils alternately with the passing of water through the still cooling coils.

4. In a refrigerating apparatus, a still comprising an outer casing, inner casings, cooling coils in said inner casings, a manifold, and delivery pipes from said manifold sealed through the wall of each of said inner casings and connecting thereto through a plurality of small holes.

5. In a refrigerating apparatus, a still comprising an outer casing, inner casings, cooling coils in said inner casings, a manifold, delivery pipes from said manifold sealed through the wall of said inner casings and connecting thereto through a plurality of small holes, and coverings of asbestos tubing for said delivery pipes and the holes therein.

6. In a refrigerating apparatus, a still comprising an outer casing, inner casings, a cooling coil in each of said inner casings, a manifold, a delivery pipe from said manifold sealed through the wall of each of said inner casings and connecting thereto through a plurality of small holes, and an absorbent material in said inner casings.

7. In a refrigerating apparatus, a still comprising an outer casing, inner casings, a cooling coil in each of said inner casings, a manifold, a delivery pipe from said manifold sealed through the wall of each of said inner casings and connecting thereto through a plurality of small holes, and an absorbent material such as calicum chloride and a cementitious material in said inner casings.

8. In a refrigerating apparatus, a still comprising an outer casing, inner casings, cooling coils in said inner casings, a manifold, a one-way connection from said manifold to the cooling apparatus of said refrigerating apparatus, a one-way connection from the said cooling apparatus to said manifold, and a delivery pipe from said manifold sealed through the wall of each of said inner casings and connecting thereto through a plurality of small holes.

9. In a refrigerating apparatus, a still through the wall of each of said inner casings and connecting therewith through a plurality of small holes, and coverings of asbestos tubing for said delivery pipes and the apparatus therein. 10
- In testimony whereof I hereto affix my signature.

FREDERICK G. KEYES.
